SIGN

Evert F. Johnson, Oil City, Pa., assignor to The
Pennzoil Company, Oil City, Pa., a corporation
of Pennsylvania

Application January 24, 1936, Serial No. 60,653

5 Claims. (Cl. 40—128)

This invention relates to improvements in signs, proposing a construction which includes a sign body bearing original display matter of a more or less permanent character and a flexible covering bearing new display matter of a special or seasonal import which is adapted to fit upon the sign body to superpose the new display matter upon the original display matter, the sign body serving as a frame for the covering 10 when the latter is arranged in the manner described.

A further object is to provide for facility in applying the covering to, and in removing it from, the sign body.

15 The invention is illustrated in the accompanying drawing in which:

Figure 1 is a view in elevation of a sign in which the features of the invention are incorporated.

20 Figure 2 is a horizontal section taken along line 2—2 of Figure 1.

Figure 3 is an enlarged vertical section taken along line 3—3 of Figure 1.

25 Figure 4 is an enlarged perspective view of one of the clips employed in removably securing the covering upon the sign body.

Figure 5 is a perspective view of the covering.

The sign, as illustrated, includes a plate 6 which is suspended from an arm 7, the said arm being carried by a standard 8 and being formed to provide horizontal and guy sections 9 and 10, respectively. The plate 6 is connected to the horizontal section of the arm 7 by a hanger 11 and an angle member 12, the former being secured at its mid section, as by rivets 13, to the top flange 14 of the latter and being formed at its opposite ends with inverted U-shaped projections 15 which are suitably apertured to accommodate the arm section 9. The side flange 16 of the angle member 12 is secured to the upper marginal edge of the plate 6 by nut-and-bolt fastenings 16a. The construction described enables the plate 6 to swing upon the arm 7, suitable stops 17 which are formed or provided upon the arm section 9 co-operating with the projections 15 to hold the plate in the desired spaced relation with respect to the standard 8. The opposite faces of the plate 6 bear display matter 18 which, as illustrated, is painted upon the plate and hence is intended to be of a more or less permanent character, it being understood that a single face only of the said plate may be utilized if this is preferred.

In accordance with the invention means is provided, whereby special or seasonal display mat-

ter may be exhibited by the sign. The said means is preferably in the form of a flexible covering and, as shown, comprises an envelope 19 which is adapted to fit upon the plate 6 in the manner of a slip cover, the sides of the envelope 19 bearing the special or seasonal display matter which is indicated at 20 and which is superposed upon the display matter 18 when the envelope is arranged upon the plate. The envelope 19 may be formed of any suitable material such as, for example, paper or cloth. As illustrated, it is formed from two sheets of paper 21 which are sewed together along three sides as indicated at 22, the paper sheets preferably being treated with a suitable water-proofing composition. The free edges of the sheets 21 define the mouth of the envelope, the location of the mouth being predetermined in accordance with the manner in which the plate is to be supported.

Means is provided for removably securing the envelope 19 upon the plate 6. The said means includes inverted U-shaped clips 23 (Figure 4) which fit over the upper edge of the plate and are secured thereto by the nut-and-bolt fastenings 16a, the bolts of the said fastenings passing through openings 24 formed in the legs of the clips. At their lower ends portions of the legs of the clips are struck outwardly in opposite directions to provide hooks 25. The latter co-operate with eyelets 26 which are carried by the top edges of the side walls of the envelope to removably secure the envelope upon the plate 6. The envelope, as thus supported, covers substantially the entire area of the plate, the latter providing a frame for holding the walls of the envelope straight.

It will be apparent that the plate 6 not only bears display matter of a more or less permanent character but is also available as a frame for envelopes bearing display matter of a special or seasonal import, the walls of the envelope covering and concealing the original display matter. When an envelope is arranged upon the plate and it is desired to again employ the original display matter or to make use of display matter different from that borne by either the plate or the envelope, the latter may be removed from the plate by raising it slightly to disengage the eyelets 26 from the hooks 25. The envelope can then be slipped off the plate 6 and be replaced by one bearing the new display matter. The application and removal of the envelopes in the manner described can be accomplished with facility and without the aid of tools. The sign has the further advantage that the clips 23 can be em- 55

ployed in connection with standard sign parts, the clips, in the embodiment illustrated, utilizing the conventional nut-and-bolt fastenings which are employed in securing the plate 6 to the angle member 12.

I claim as my invention:

1. The combination with a sign body having a face which bears display matter and means for connecting said body to a supporting structure, 10 of an envelope which is adapted to fit upon said body in the manner of a slip cover and which is adapted to utilize said body as a frame, said envelope bearing display matter which is superposed upon that borne by said face and means 15 for removably securing said envelope upon said body.

2. The combination with a sign body having a face which bears display matter and means for connecting one side only of said body to a supporting structure, of an envelope which is adapted 20 to fit upon said body in the manner of a slip cover to utilize said body as a frame, said envelope bearing display matter of a different import from that borne by said face and means for 25 removably securing said envelope upon said body.

3. The combination with a sign body having a face which bears display matter and means for connecting said body to a supporting structure, 30 of an envelope which is adapted to fit upon said body in the manner of a slip cover and to utilize

said body as a frame, said envelope being formed of water-proofed paper and bearing display matter of a different import from that borne by said face and means for removably securing said envelope upon said body.

5

4. The combination with a sign body having a face which bears display matter, of an envelope which is adapted to fit upon said body in the manner of a slip cover, said envelope bearing display matter of a different import from that borne 10 by said face and U-shaped clips secured along one edge of said body which are formed to provide hooks, said envelope having eyelets which are adapted to fit over said hooks, whereby to removably secure said envelope upon said body.

15

5. The combination with a sign body having a face which bears display matter, and means for supporting said body from a structure, said means including bolts, of an envelope which is adapted 20 to fit upon said body in the manner of a slip cover, said envelope bearing display matter of a different import from that borne by said face and U-shaped clips along one edge of said body which are formed to provide hooks, said clips being secured to said body by said bolts, said envelope 25 having eyelets which are adapted to fit over said hooks, whereby to removably secure said envelope upon said body.

20

EVERT F. JOHNSON.
